UNITED STATES PATENT OFFICE.

JAMES T. WATKINS, OF MOSSY CREEK, TENNESSEE, ASSIGNOR OF ONE-HALF
TO JAMES MADISON HOLLOWAY, OF MACON, GEORGIA.

DESIGN FOR A MEMBER FOR SPOKE-SOCKETS.

SPECIFICATION forming part of Design No. 29,987, dated January 10, 1899.

Application filed December 13, 1898; Serial No. 699,183. Term of patent 14 years.

To all whom it may concern:

Be it known that I, JAMES T. WATKINS, a citizen of the United States, residing at Mossy Creek, in the county of Jefferson and State of Tennessee, have invented and produced a new and original Design for Devices for Fastening Wheel-Spokes to Wheel-Fellies, of which the following is a specification.

My invention relates to a new and original design for a member of a spoke-socket, and is illustrated in the accompanying drawings, in which—

Figure 1 is a reverse view, and Fig. 2 an obverse view, of the member of the spoke-socket.

The leading feature of my design consists in a member of a spoke-socket formed with an upright portion or flange having perforations, a ledge projecting substantially at right angles to said upright flange, and having an upright flange with straight side portions formed with perforations, said straight side portions being joined by a semicircular wall forming a semicircular recess having a flat bottom.

In the said drawings, the reference-numeral

1 indicates the upright or vertical flange, having perforations 2, and the numeral 3 indicates the horizontal ledge. Extending from this horizontal ledge is an upright flange having straight flat side portions 4 formed with perforations 5, said side portions being joined together by a semicircular wall 6, forming a semicircular recess 7, which has a flat bottom 8.

Two members, counterparts of each other, constitute a complete spoke-socket.

My design presents a member of a spoke-socket having a novel, pleasing, and distinguishing appearance.

Having thus described my invention, what I claim is—

The design for a member of a spoke-socket substantially as herein shown and described.

In testimony whereof I have hereunto set my hand in presence of two subscribing witnesses.

JAMES T. WATKINS.
